UNITED STATES PATENT OFFICE.

JEREMIAH B. SWEET, OF HUTCHINSON, KANSAS.

SHAKER.

Application filed July 28, 1922. Serial No. 578,246.

To all whom it may concern:

Be it known that I, JEREMIAH B. SWEET, a citizen of the United States, residing at Hutchinson, in the county of Reno and State 5 of Kansas, have invented a new and useful Shaker, of which the following is a specification.

The device shown, described and claimed is a condiment shaker of the sort shown in 10 my Patent 1,411,594 and, in addition to improving generally, and enhancing the utility of the patented device, the present invention aims, first, to provide novel means for controlling the outlet; second, to provide novel 15 means for keeping the outlet open; and third, to simplify the casing which is assembled with the receptacle containing the condiment.

In the drawings:—Figure 1 shows in section, a device constructed in accordance with the invention; Figure 2 is a plan; Figure 3 is a section on the line 3—3 of Figure 1; Figure 4 is a section on the line 4—4 of Figure 3.

The numeral 1 marks a receptacle. The 20 numeral 2 designates a casing detachably held, by threading 3, or otherwise, either on the top or base of the receptacle 1, the casing including an inner wall 4 and an outer wall 5 spaced to form a compartment 6. Inlets 7 are struck from the wall 4, and open into the receptacle 1 in a direction substantially at right angles to the axis of the receptacle. The casing 2 is provided 25 in its periphery with an outlet 8 for the compartment 6, and in the form of an elongated slot. A cleaner for the outlet 8 is provided and it is in the form of a pendulum 9, the outer end of which moves 30 in the outlet 8, the inner end of the pendulum being pivoted at 10 to the inner wall 4, the pendulum being adapted to swing on the wall 4 in the direction indicated in Figure 3, at right angles to the axis of the receptacle 1. The pendulum or cleaner is of 35 particular use when salt is dispensed, and the pendulum may be omitted when desired. A disk or plate 11 is mounted on the outer wall 5 of the casing 2 and has a depending

arcuate flange 12 cooperating with the edge 50 of the casing 2 and adapted to cover the outlet 8. The disk 11 and the flange 12 may be alluded to briefly as a closure. The disk 11 has elongated slots 14 through which 55 passes a staple-shaped keeper 15 engaged with the outer wall 5 of the casing 2 and holding the closure 11—12 on the casing for right line sliding movement.

By proper manipulation of the receptacle 1, the contents thereof may be made to enter 60 the compartment 6 through the inlets 7, and may be discharged through the outlet 8 when the disk 11 is slid on the keeper 15 until the flange 12 is spaced from the outlet 8, as shown in dotted line in Figure 1. Whilst 65 the device is in operation, the outer end of the pendulum or cleaner 9 moves in the outlet 8 and keeps the same clear. The casing 2 prevents moisture from entering the receptacle 1, and this is especially true, because the disk 11 may be retracted until the flange 12 closes the outlet 8. This closure 70 11 and 12 is of particular use when sugar is dispensed, and is omitted when salt is dispensed.

I claim:—

1. In a device of the class described, a casing having an inlet and an outlet, and a cleaner mounted at its inner end to swing on the casing, the outer end of the cleaner being movable in the outlet, and the center of mass of the cleaner being so located with respect to its inner end, that the cleaner will swing pendulum-wise when the casing is moved.

2. In a device of the class described, a casing having an inlet and a side outlet; a cleaner mounted at its inner end to swing on the casing, the outer end of the cleaner being movable in the outlet; a closure having a flange; and means for mounting the closure on the casing for right line sliding movement, whereby the flange may move to and from the outlet.

In testimony that I claim the foregoing as my own, I have hereto affixed my signature.

JEREMIAH B. SWEET.
